UNITED STATES PATENT OFFICE

PETER CURTIS KG EUNE, OF PHILADELPHIA, PENNSYLVANIA

CONTROLLING DEVICE FOR BURGLAR AND FIRE ALARMS

Application filed May 20, 1930. Serial No. 453,960.

My invention relates to an alarm and call bell adapted to be sounded by pressing a push button.

A purpose of my invention is to provide commercial bells that have hitherto been set into operation by finger pressure upon an outwardly pressing button with an alternative screw deflection of the button. I am thus enabled to touch the starting screw and set the bell ringing after which it continues to ring irrespective of the operator until any wound-up mechanism runs down or until the position of the starting screw has been changed.

15 A further purpose is to mount upon a common base a push-button type of bell and an outside bracket carrying a starting screw adapted to engage the push button. I prefer to use a spring-operated bell in which the push button is adapted to rotation to wind up the operating spring and also adapted to inward deflection to ring the bell after the spring has been wound up, the bell ringing continuously as long as the button is deflected and until the spring mechanism has become unwound.

20 30 A further purpose is to provide a bracket carrying a set screw which may be swung into and out of registry with the push button allowing the bell to be used as an ordinary tap bell.

Further purposes will appear in the specification and in the claims.

I have elected to show one form only of my invention, selecting a form that is practical and efficient in operation and which well illustrates the principles involved.

Figure 1 is a side elevation of a preferred structure embodying my invention.

40 Figure 2 is a top plan view of Figure 1.

Figure 3 is a vertical section taken upon the line 3—3 of Figure 2.

Figure 4 is a horizontal section on the line 4—4 of Figure 3.

45 Figure 5 is a detail section upon the line 5—5 of Figure 3.

Like numerals refer to like parts in all figures.

50 Describing in illustration and not in limitation and referring to the drawings:—

In the past call and alarm bells operated by finger depression of a push button have been justly popular, but nevertheless have been subject to the disadvantage that they are not adapted to ring except during finger depression. This had necessitated continuous finger pressure upon the operating button as long as the bell is to ring, which is often quite undesirable.

By my invention I am enabled to start the bell ringing and let it continue to ring without attention as long as desired. This feature is often very advantageous as in case of alarm bells where the person starting the alarm may have most urgent need to attend to other matters, or in the case of a call bell where it may be desirable to have a bell ring continuously until there has been a response to the call.

I arrange the bracket in position to be moved so as to place a set screw carried by the bracket in position to engage the tap member of the bell to cause a continuous ring or by swinging the bracket away from the position mentioned, to allow use of the bell as an ordinary tap bell.

While I am well aware that my invention is adapted to operate with electrically operated bells as well as to the spring-type I anticipate its widest application to be with the latter type of bell and have for this reason illustrated it with the spring-type of bell.

In spring-operated bell units, the spring, clapper and most of the operating mechanism are usually surrounded by the bell, with the push button coaxial with and outside the bell.

I show in the figures a commercial bell unit 6 and a bracket 7 mounted upon a common base 8, the bracket supporting a screw 9 threaded in its outer end and adapted to engage and deflect an outwardly pressing push button 10 which is coaxial with the bell proper 11 and serves also as key to wind up the operating mechanism inside the bell.

The bottom plate 12 of the commercial bell supports an upper plate 13 upon suitable post 14.

An operating spiral spring 15 has one end rigidly fastened to a king post 16 journaled between the plates 12 and 13, the other end

of the spring being fastened to an anchor post 17.

The upper plate carries a central sleeve member 18 which supports the bell 11 above 5 and coaxially with the king post.

A clapper 19 pivotally supported at 20 is operated from the wound-up spring by the king post 16, gear wheels 21 and 22 and escapement 23, pawl and ratchet mechanism 24 10 holding the king post from turning in reverse direction.

Normally operation of the clapper is prevented by its engagement at 25 with one arm of a rocker member 26 pivoted at 27 above 15 the upper plate.

The rocker 26 is spring-pressed at 28 so as to press against the clapper arm and has an upper arm 29 that extends through an opening 30 in the sleeve 18 into a groove 31 in the 20 lower end of the push button which is thus maintained in its outer position by the rocker arm.

The king post is extended above the upper plate, presenting a square winding post 32 25 fitting into a square opening 33 in the depression button.

The bracket 7 may conveniently be made of a round rod flattened at 34 where it engages the base 8 and extending upwardly and 30 then radially inwardly to provide a threaded seat 35 for the starting screw.

Desirably, the outer end of the push button is recessed at 36 to receive the inner end of the starting screw. The bracket is angularly 35 adjustable upon the base about its holding screw 37 to permit it to be turned out of the way for winding. However, the spring can be wound while the bracket is in place with the starting screw alined with the push but- 40 ton.

In operating the alarm, the starting screw 9 is screwed downwardly one or two turns, to 45 downwardly depress the push button 10, after which the bell rings continuously by any suitable mechanism until the starting screw is turned back to its original position or until the mechanism runs down.

In the illustration the downward deflection of the push button rocks the release member 26 to release the bell clapper 25 which then operates under the action of the spiral spring 15 until the screw 9 is moved back to 50 stopping position or until the spring 15 runs down.

In view of my invention and disclosure variations and modifications to meet individual whim or particular need will doubtless 55 become evident to others skilled in the art, to obtain all or part of the benefits of my invention without copying the structure shown, and I, therefore, claim all such in so far as they fall within the reasonable spirit and scope of my invention.

Having thus described my invention what

I claim as new and desire to secure by Letters Patent is:—

1. A bell, a push button spring-pressed outwardly, and mechanism adapting the bell to ring if there be and during inward deflection of the button, in combination with a bracket outside the bell and a screw adjustably threaded in the bracket adapted to engage and inwardly depress the button to ring the bell. 70

2. A bell, a push button spring-pressed outwardly, and mechanism adapting the bell to ring if there be and during inward deflection of the button, in combination with a shiftable bracket outside the bell and a depressing member carried by the bracket and adapted to hold the mechanism in ringing position in one bracket position. 80

3. A supporting base, a bell, a push button coaxial therewith normally spring-pressed outwardly, and mechanism adapting the bell to ring during inward deflection of the button from its normal outward position, in combination with a bracket from the base outside the bell and a screw adjustably threaded in the bracket adapted to engage and deflect the button. 85

4. A supporting base, a bell, a combined push button coaxial therewith, and spiral spring mechanism adapted to be wound up by rotation of the push button and key and when wound adapting the bell to ring during inward deflection of the button from its normal outward position, in combination with a bracket having angularly adjustable support 95 upon the base outside the bell and a screw adjustably threading the bracket, adapted in one position of the bracket to engage and inwardly deflect the button. 100

5. Bell mechanism including a base, a rotatable post, a spiral spring fastened to and wound around the post, an anchor for the outer end of the spring, a clapper, an escapement mechanism adapted to operate the clapper, gearing between the post and escapement, 105 a rocker arm normally spring-pressed into the clapper to prevent its operation, a bell coaxial with the post adapted to be rung by the operation of the clapper, and a key and release member coaxial with and surrounding the outer end of the post adapted to wind up the spring when rotated and to release the clapper by depressing the rocker when deflected toward the base, in combination with a bracket rigid with the base and an adjustable screw presented and supported by the bracket in position to engage the key and release member to operate the release. 110

PETER CURTIS KO EUNE.
